GOOGLES

Harris King Halikman, East Boston, Mass.

Application July 15, 1932, Serial No. 622,593

2 Claims. (Cl. 88—43)

This invention relates to an improvement in goggles, especially pertaining to the bridge for the goggles which connects the lenses together, and to an improved construction of nose pieces 5 mounted on said bridge.

The object of the invention is to provide a pair of goggles in which the lenses are pivotally mounted upon the bridge and, further, in a construction in which the nose piece is pivotally 10 mounted on the bridge.

The invention consists in the combination and arrangement of parts set forth in the following specification and particularly pointed out in the claims.

15 Referring to the drawing:

Fig. 1 is a plan view of my improved bridge for goggles with the lenses attached thereto and broken away, the same being made on a very much enlarged scale.

20 Fig. 2 is a rear elevation of the bridge and nose pieces, together with the lenses, also broken away and made upon an enlarged scale.

Fig. 3 is a sectional elevation taken on line 3—3, Fig. 2.

25 Fig. 4 is a plan view of a modified form of bridge in which the nose piece is pivotally mounted on the bridge to swing about a horizontal pivot.

Fig. 5 is a sectional elevation taken on line 30 5—5, Fig. 4.

Like numerals refer to like parts in the several views of the drawing.

Referring to Figs. 1, 2 and 3, 6 is a bridge embodying a vertical center piece 7 constituting 35 a support and manufactured of a single piece of sheet metal, bent inwardly at its lower end, see Fig. 3, to form a U 8, the U consisting of legs 9 and 10 constituting parallel front and rear walls respectively and a cross piece 11 connecting the 40 legs 9 and 10 together. The upper end of the center piece or plate 7 is bent inwardly to form a hook 12, and a staple 13 is supported upon the center piece 7 with its cross piece 14 held in the hook 12 and the legs 15 and 16 of the staple 45 extending downwardly and into the cross piece 11 of the U 8.

A pair of lens holders 17 and 18 are pivotally supported upon the legs 15 and 16 respectively. These lens holders consist of segmental clamp 50 portions 19 and 20 which hold the rims 21 and 22 of the lenses 23 and 24 and, further, the lens holders embody therein arms 25 and 26 which terminate at their adjacent ends in tubular portions 27 and 28 pivotally mounted respectively on the 55 legs 15 and 16 of the staple 13.

A pair of sheet metal arms 29 and 30 project from opposite sides of the inner leg 10 of the U 8 diverging from each other and terminating in hooks 31 and 32. To the hooks 31 and 32 are attached or made integral a pair of nose 60 pieces 33 and 34. The nose pieces are oppositely disposed to each other and extend in a vertical direction on the free ends of the arms 29 and 30 and are interposed between said arms. It will thus be seen that the lenses are pivotally 65 mounted upon the bridge 6 and that the nose pieces can be adjusted toward and away from each other by bending the arms 29 and 30 and can be adjusted relatively to said arms by bending the hooks 31 and 32 so that the nose pieces 70 are rendered adjustable to fit different forms of noses.

In Figs. 4 and 5 a modified form of my invention is illustrated in which the lenses and their arms and the lens holders 17 and 18 are 75 the same as in the form of my invention illustrated in Figs. 1 to 3 inclusive, and these lens holders are mounted upon a staple 13 which is the same as the staple 13 in Figs. 1, 2 and 3. The center piece 35, however, in the form of my 80 invention illustrated in Figs. 4 and 5 differs from the center piece 7 in Figs. 1, 2 and 3, in that the lower end 36, instead of being bent to form a U, is bent inwardly at right angles and terminates in a tubular portion or eye 37, through 85 which a pivotal pin 38 extends and a nose piece 39 is provided which extends transversely of the nose and rests upon the bridge thereof. This nose piece has ears 40 projecting therefrom and pivotally mounted upon the pivotal pin 38, so 90 that the nose piece 39 can tip to adjust itself to different forms of noses, around a horizontal pivot. Other than the particular construction of the center piece 35 and the manner in which the nose piece 39 is mounted thereon, the goggles 95 illustrated in Figs. 4 and 5 are the same as those illustrated in Figs. 1, 2 and 3, insofar as the lenses and lens holders are concerned.

I claim:

1. A bridge for goggles having, in combination, 100 a vertical center piece constituting a support and consisting of a piece of sheet metal bent inwardly at its lower end to form a U, a pair of sheet metal arms projecting from opposite sides of the inner leg of said U, a pair of oppositely disposed nose pieces on the free ends of said arms, the upper end of said center piece being bent inwardly to form a hook, a staple supported on said center piece with its cross piece held in said hook and its legs projecting down- 110

wardly and into the cross piece of said U, and a pair of lens holders pivotally supported on said legs.

5 2. A bridge for goggles having, in combination, a center piece constructed of a single piece of sheet material bent inwardly at its lower end to form parallel front and rear walls, said rear wall being extended from opposite edges thereof to provide oppositely extending arms each of which

10

terminates in a nose piece adapted to contact with the side of the nose, the upper end of said center piece being bent inwardly to form a hook, a staple supported upon said center piece with its cross piece positioned in and held by said hook and the legs thereof projecting downwardly and through the center piece, and a pair of lenses pivotally mounted upon said legs.
